UNITED STATES PATENT OFFICE.

CROMWELL A. B. HALVORSON, JR., OF LYNN, MASSACHUSETTS, ASSIGNOR TO GENERAL ELECTRIC COMPANY, A CORPORATION OF NEW YORK.

ARC-LAMP.

No. 905,515.

Specification of Letters Patent.

Patented Dec. 1, 1908.

Application filed April 6, 1907. Serial No. 366,669.

To all whom it may concern:

Be it known that I, CROMWELL A. B. HALVORSON, Jr., a citizen of the United States, residing at Lynn, county of Essex, State of 5 Massachusetts, have invented certain new and useful Improvements in Arc-Lamps, of which the following is a specification.

My invention relates to electric arc lamps and particularly to that type wherein a 10 "lifting" clutch and a "holding" clutch are provided for feeding and positioning one of the electrodes.

In a common form of arc lamp, one of the electrodes, at each feeding operation, is moved toward the companion electrode a 15 distance equal to the normal arc length plus an additional increment corresponding to the consumption of the electrode which has taken place since the previous feeding action. 20 After this electrode has been brought into engagement with the companion electrode, it is again permitted to drop through a fixed distance which determines the normal arc length. The movement through a variable 25 distance in the one direction is brought about by a so-called "lifting" clutch, while the fixed movement in the opposite direction is controlled by a "holding" clutch; and, since the proper adjustment of the arc 30 length and therefore the uniformity of the light depends upon a reliable controlling mechanism for the holding clutch, the construction and arrangement of that mechanism is of the utmost importance.

35 The present invention has to do particularly with the control of the holding clutch, and it has for its object to provide a simple and durable arrangement of parts whereby the clutch shall at all times operate reliably 40 and uniformly to perform its intended functions.

The various features of novelty which characterize my invention will be herein- 45 after pointed out with particularity in the claims, but for a full understanding of the invention and of its various objects and advantages, reference may be had to the following detailed description taken in connection with the accompanying drawing, 50 wherein:

Figure 1 shows in side elevation, with the casing and globe removed, a lamp equipped in accordance with a preferred form of my invention; and Fig. 2 is a diagrammatic 55 view of the lamp and its connections.

In the drawing I have shown a well-known form of luminous arc lamp having a non-consuming positive electrode which occupies a fixed position in the lamp, together with a negative electrode which consumes 60 and gives off the vapors to maintain the arc and which is intermittently fed towards the positive electrode to compensate for the wasting away of the electrode material of which it is composed. While my invention 65 is particularly applicable to lamps of this type, it will of course be understood that in the broader aspects of my invention its various features are applicable to lamps of various other types, wherein it is desired to 70 make use of a holding clutch which shall permit an electrode to be fed through variable distances in one direction and limit the movements of the electrode in the opposite direction to fixed distances. 75

Referring to the drawing, 1 indicates the hood, 2 the platform of the lamp, and 3 a chimney which connects these members together and forms the backbone of the lamp. 4 is a fume box mounted beneath the platform and in communication with the lower end of the chimney. 5 is an electrode having wings 6, 6, which are supported by the walls of the fume box. 7 is an electrode which is supported in a holder 8 beneath and 80 in alignment with the upper electrode. The holder 8 is in turn carried by an elongated tube 9 which projects upwardly through the platform and is guided at its upper end by a rod 10 which extends into it. 11 is a 85 clutch which is carried by the armature 12 of the feeding magnet 13 and engages with the tubular electrode support so as to lift this support and the lower electrode when the feeding magnet is energized and attracts 90 its armature. All these parts may take any 95 usual or preferred forms since they in themselves form no part of the present invention but are merely illustrated as indicative of general types of elements which go to make 100 up an arc lamp.

The clutch 11, or "lifting" clutch, serves to move the electrode 7 toward the companion electrode until it is brought into engagement therewith, the extent of movement 105 being dependent upon the distance which separates the electrodes when the movement is begun. A second clutch 14, or "holding" clutch, is provided for controlling the movement of the electrode 7 away from the other 110.

electrode when striking the arc. The holding clutch may take any desired form which will permit the supporting tube for the lower electrode to move upwards through it, 5 but which grips the tube and moves with it in the downward direction. The holding clutch is mounted upon no fixed support but is movable freely in a vertical direction between a pair of adjustable stops 15 and 16 10 carried upon a rod 17 which extends upwardly from the platform of the lamp. The free end of the holding clutch is pivotally connected to the lower end of a rod or link 18 which is carried at its upper end 15 from one end of a lever 19. The lever 19 is pivoted intermediate its ends upon a bracket 20 secured to the frame of the lamp. The end of the lever 19 opposite that to which the link 18 is secured is in the form of, or 20 has secured thereto, an armature 21 of magnetic material which is within the field of the feeding magnet and, when this magnet is energized, is attracted thereby so as to oscillate the lever about its pivot. A dash- 25 pot 22 is secured to the lever 19 and is arranged so as to permit free oscillation of the lever in a direction which carries its armature toward the electro-magnet but to retard the oscillation of the lever in the opposite 30 direction.

The operation of the parts described is as follows: When current is turned on the lamp, the feeding magnet is energized and, operating through the lifting clutch, raises 35 the lower electrode until it engages with the upper electrode. At the same time the armature 21 is attracted and the lever 19 is oscillated so as to carry the link 18 and the holding clutch upwards. If desired, the attraction 40 of the two armatures of the electromagnet may be made to occur in such a manner that the holding clutch assists the lifting clutch during the first portion of movement of the latter to raise the lower electrode. 45 The upward movement of the holding clutch is, however, limited by the stop 15, and when the holding clutch engages with this stop the further upward movement of the electrode must be effected by the lifting clutch alone. The drawing shows in full 50 lines the positions of the parts after the lower electrode has completed its upward movement. When now the feeding magnet is deenergized, as will be hereinafter de- 55 scribed, the lifting clutch is no longer operative to support the lower electrode and this electrode begins to descend, carrying with it the holding clutch. The holding clutch is unable to drop freely because of the dash- 60 pot and, since the lower electrode can travel no faster than the holding clutch, it must also descend slowly, thereby gradually drawing an arc between its upper end and the companion electrode. The downward move- 65 ment of the parts continues until the hold-

ing clutch comes to rest upon the lower stop 16, whereupon further movement both of the holding clutch and the lower electrode ceases. The positions of the parts are now as shown in dotted lines on the drawing. 70 After the lower electrode has burned away sufficiently to make it desirable to feed it toward the other electrode, the feeding magnet is again energized and the parts are once more brought to the positions shown in full 75 lines.

It will be seen that the arrangement for controlling the holding clutch consists of but a few simple parts which may be strongly made and which require no attention in order to insure their proper operation. By adjusting the stops 15 and 16, the extent through which the holding clutch may move, and therefore the length of arc, 80 may be varied at will without in any way 85 changing the manner in which the operating mechanism for the holding clutch performs its functions or the reliability with which it performs such functions.

The circuit connections of the lamp and the manner and method of controlling the feeding magnet may be varied to suit the type of lamp and the service to which it is to be put. In Fig. 2 I have shown diagrammatically a well known arrangement of 90 circuits and regulating devices which is in common use in lamps of the general type illustrated, and which may be used to advantage in lamps embodying the present invention. Thus, in addition to the main 95 magnet 13, there are two other magnets, 23 and 24, which control, respectively, the contacts 25 and 26 of a cut-out switch for the main magnet. Magnet 23 has its coil in series with the electrodes, while magnet 24 100 is a shunt magnet which is connected directly across the line in series with the coil of the main magnet. In the diagram the parts are shown in the positions which they 105 occupy just as the two electrodes are brought into engagement with each other. It will be seen that at this time current flows from line 27, through resistance 28, through contacts 25, 26, through the coil of the main magnet, back to line 29. As soon as good 110 contact is made between the two electrodes, however, current flows from line 27, through the coil of magnet 23, through the electrodes, and thence back to line 29. Magnet 23 is 115 energized and lifts the contact 25 associated therewith, thereby opening the shunt around the magnet 24 so that the coil of the main magnet is now connected across the line in series with the high resistance shunt magnet. The main magnet is, therefore, no longer 120 operatively energized, and it permits its armature 12 to drop and also permits the lower electrode to oscillate the lever 19 so as to carry the armature 21 away from the end 125 of the main magnet. When the arc breaks 130

or becomes so long that its resistance is sufficient to cause the magnet 24 to be operatively energized, contacts 25 and 26 are again brought into engagement with each other 5 and another feeding operation is effected.

What I claim as new and desire to secure by Letters Patent of the United States, is,—

1. In an arc lamp, a movable electrode, a lifting clutch and a holding clutch operating 10 on said electrode to respectively move it in one direction and to limit the movement thereof in the opposite direction, a magnet for operating said lifting clutch, and an auxiliary armature associated with said 15 magnet for controlling said holding clutch.

2. In an arc lamp, a movable electrode, a lifting clutch and a holding clutch operating 20 on said electrode to respectively move it in one direction and to limit its movement in the opposite direction, an electromagnet, and independent armatures associated with 25 said magnet to control said clutches.

3. In an arc lamp, a movable electrode, a lifting clutch for moving said electrode in 25 one direction, a holding clutch for limiting the movement of the electrode in the other direction an electromagnet having an armature for operating the lifting clutch, a second armature for the same electromagnet 30 and means for supporting said holding clutch from said second armature.

4. In an arc lamp, a movable electrode, a lifting clutch for elevating the electrode, a holding clutch for limiting the lowering 35 movement of the electrode, upper and lower stops between which the holding clutch is free to move, an electromagnet for operating said lifting clutch, and an auxiliary armature associated with said electromagnet and 40 connected to the holding clutch to move it into engagement with the upper stop upon the energization of the electromagnet.

5. In an arc lamp, a gravity-actuated electrode, a lifting clutch for raising said electrode against the action of gravity, a holding clutch for limiting the lowering movement 45 of the electrode, upper and lower stops between which the holding clutch is free to move, an electromagnet for operating said lifting clutch, an auxiliary armature associated with the electromagnet for moving the holding clutch into engagement with the upper stop upon the energization of the electromagnet, and the holding clutch being 50 carried into engagement with the lower stop by the electrode upon the deenergization of the electromagnet.

6. In an arc lamp, a movable electrode, a lifting clutch for moving the electrode in 55 one direction, a holding clutch for limiting

the movement of the electrode in the opposite direction, one electromagnet for actuating both clutches, and a retarding device acting on said holding clutch independently of the lifting clutch.

65

7. In an arc lamp, a movable electrode, a lifting clutch for elevating the electrode, a holding clutch for limiting the lowering movement of the electrode, upper and lower stops between which the holding clutch is free to move, an electromagnet for operating said lifting clutch, and an auxiliary armature associated with said electromagnet and connected to the holding clutch to move it into engagement with the upper stop upon 70 the energization of the electromagnet, and a retarding device acting on said holding clutch independently of the lifting clutch for limiting the rate of movement of the holding clutch towards the lower stop.

80

8. In an arc lamp, a gravity-actuated electrode, a lifting clutch for raising said electrode against the action of gravity, a holding clutch for limiting the lowering movement of the electrode, upper and lower stops 85 between which the holding clutch is free to move, an electromagnet for operating said lifting clutch, an auxiliary armature associated with the electromagnet for moving the holding clutch into engagement with the upper stop upon the energization of the electromagnet and the holding clutch being carried into engagement with the lower stop by the electrode upon the deenergization of the electromagnet, and a retarding device acting 95 on said holding clutch independently of the lifting clutch for limiting the rate of movement of the holding clutch towards the lower stop.

9. In an arc lamp, a gravity-actuated electrode, a lifting clutch for raising the electrode, a floating holding-clutch arranged to move between upper and lower stops, a retarding device connected to the holding clutch and arranged to limit the rate of 105 movement thereof toward the lower stop, and an electromagnet for operating the lifting clutch and for raising the holding clutch into engagement with the upper stop and into clutching engagement with the electrode, said holding clutch being moved into 100 engagement with the lower stop by means of the electrode.

In witness whereof, I have hereunto set my hand this second day of April, 1907.

CROMWELL A. B. HALVORSON, JR.
